UNITED STATES PATENT OFFICE.

EARL B. HORNER AND LAFAYETTE HOLT, OF BURLINGTON, NORTH CAROLINA.

MACHINE FOR TREATING ROAD-BUILDING MATERIAL.

Application filed March 5, 1923. Serial No. 622,994.

The present invention relates to a road making machine, and aims to provide a novel and improved apparatus for treating the dirt at the surface of a road to produce a desirable finished surface as the machine advances along the road.

Another object is the provision of such a machine having novel means for loosening the dirt and subjecting same to the action 10 of flames for heating the dirt and burning therefrom any vegetable matter, insects, and other foreign matter that would be liable to cause the subsequent disintegration of the layer forming the surface of the road.

15 A further object is the provision of a novel arrangement for treating the loosened dirt preparatory to the rolling or compression thereof to form a hard layer capable of withstanding traffic conditions.

20 A still further object is the utilization of the heat given off during the treatment of the dirt, for keeping the roller or packing means and also a tank of tarvia or other surfacing solution warm, in order that the 25 roller or packing means can be kept warm to better compress the dirt, and in order that the tarvia or surfacing solution can be kept warm so as to flow freely to be sprayed on the layer of packed or compressed dirt.

20 The invention also has for an object to improve the machine generally in its construction and details, to enhance the utility and efficiency thereof.

With the foregoing and other objects in 35 view, which will be apparent as the description proceeds, the invention resides in the construction and arrangement of parts, as hereinafter described and claimed, it being understood that changes can be made within 40 the scope of what is claimed, without departing from the spirit of the invention.

The invention is illustrated in the accompanying drawings, wherein:—

45 Fig. 1 is a side elevation of the improved machine.

Fig. 2 is a plan view thereof, portions being broken away.

Fig. 3 is a vertical section on the line 3—3 of Fig. 2.

50 Fig. 4 is a fragmentary elevation showing the dirt loosening drum and adjacent portions on a slightly larger scale than in Fig. 1.

55 The machine comprises a suitable frame 7 supported by the rear roller 8 and the front

steering roller or wheel 9. The roller 8 is of suitable width, according to the width of the strip of road which is to be treated, and said roller provides means for packing or compressing the dirt. The axle 10 of the roller 8 is journaled in bearings 11 secured to the frame. The front roller or wheel 9 is preferably smaller than the roller 8 and is used for supporting the forward end of the frame and for steering the machine. 60 The axle 12 of the roller or wheel 9 is mounted in an arch or fork 13 having a vertical shaft 14 journaled in the forward portion of the frame for angling the roller or wheel 9 to steer the machine. The steering gear, as shown, includes a worm wheel 15 secured on the shaft 14 and meshing with a worm 16 secured on a transverse shaft 17 journaled in pedestals or bearings 18 mounted on the frame. The shaft 17 has hand 70 wheels 19 at opposite ends for convenience in angling the wheel or roller 9.

The machine is self-propelled from a transverse drive shaft 20 mounted on the frame and driven by a suitable engine 21. 80 Cranks 22 are journaled to the frame 7 at opposite sides and are operatively connected with the shaft 20 to be driven therefrom, and said cranks are connected by the connecting rods 23 with oscillatory arms 24 85 mounted loosely on the opposite terminals of the axle 10. The arms 24 carry pawls 25 engaging ratchet wheels 26 secured on the axle 10, whereby the oscillation of the arms 24 by the rotation of the cranks 22 90 will rotate the roller 8 for advancing the machine. The arms 24 and cranks 22 are preferably so arranged that the arms 24 move in opposite directions, to obtain a practically continuous rotation of the roller 8. 95 The arms 24 have series of apertures 27 for the connection of the rods 23 so as to change the amount of oscillation of the arms 24, which will regulate the gear ratio between the drive shaft 20 and roller 8.

100 The dirt loosening means comprises a drum 28 rotated between the rollers 8 and 9 with its axis also disposed transversely, and the drum 28 is of about the same length as the roller 8. The drum 28 is disposed below the frame for vertical movement, and has on its periphery outstanding blades 29 parallel with the axle or shaft 30 of the drum, and the blades at the bottom of the drum extend downwardly below the plane 110

which is tangent to the bottoms of the rollers 8 and 9, whereby said blades 29 dig into the dirt.

The drum or cylinder 28 is mounted for upward yielding movement, so as to pass over unyielding rocks and other obstructions. Thus, the axle 30 is journaled in bearings 31 slidable vertically in slotted guides 32 depending from the frame 7, and said bearings 10 are yieldingly depressed to their normal lowermost positions by means of coiled springs 33. The springs 33 permit the bearings 31 and axle 30 to move upwardly in order that the drum 28 can pass over an unyielding 15 object.

The drum 28 is driven from the shaft 20, by means of a sprocket wheel 34 secured on each end of the axle 30 and connected by a sprocket chain 35 with the shaft 20, and although the shaft 30 is driven at each end it 20 may be driven from one end only, if desired.

A guard or shield 36 is supported above the roller 28 to prevent the loosened dirt being thrown upwardly away from the roller, inasmuch as the roller is rotated at a 25 comparatively high speed in relation to the movement of the machine which is comparatively slow.

In the rear of the lower portion of the 30 drum 28 is located an arcuate shield 37 past which the blades 29 move, and said shield 37 is carried by arms 38 secured to the ends of the shield and mounted loosely on the axle 30 of the drum 28 between the ends of 35 the drum and the guides 32. Extending downwardly and rearwardly from the upper edge of the shield 37 is a deflector 39 over which the loose dirt is thrown from the blades 29 as they move rearwardly and 40 downwardly with the drum 28, the drum being rotated reversely to the direction of rotation of the rollers 8 and 9, or counter clockwise as seen in Figs. 1 and 4. The deflector 39 directs the loose dirt back toward 45 the road bed after being carried upwardly with the drum 28. The lower edge 41 of the shield 37 extends downwardly and forwardly under the drum 28 close to the surface of the road bed from which the dirt 50 has been removed by the drum 28, and should the shield 37 strike a rock or other nonyielding obstruction the shield can swing upwardly, inasmuch as the arms 38 extend downwardly and rearwardly so that the shield 37 trails in rear of the drum. The 55 arms 38 normally seat on stops or seats 40 carried by the lower end of the guides 32, to limit the downward movement of the shield, but permitting the shield to move upwardly in passing over obstructions.

The loose dirt which passes down from the deflector 39 is intercepted by flames directed rearwardly under the deflector 39 from a burner 42. Said burner 42 is elongated and 60 is disposed under the shield 37 and deflector

39, and is supplied with fuel through pipes 43 connected to the ends thereof and extending along the arms 38 to move therewith, the burner 42 being secured to the shield 37 to move upwardly and downwardly therewith. 70 The pipes 43 are connected by flexible couplings 44 adjacent to the axle 30 with the depending branches 45 of a fuel supply pipe 47, each branch 45 having a control valve 46 to regulate the supply of fuel to the 75 burner. A fuel tank or reservoir 48 is mounted on the frame from which the supply pipe 47 leads to carry the oil to the burner, and a main control valve 49 is provided in the pipe 47. 80

Oil is also supplied from the tank 48 to the loose dirt on the roadbed in rear of the drum 28 and burner 42. Thus, one or more depending pipes 50 have pivotal or knuckle joints 51 with the supply pipe 47, 85 and have spray nozzles 52 at their lower ends for spraying the oil on the loose dirt in rear of the drum 28 and burner 42 and in advance of the roller 8. Each pipe 50 is preferably provided with a control valve 53 for regulating the discharge of oil. The pipes 50 can be adjusted to extend downwardly at different angles in order to apply the oil to the loose dirt at most effective point between the drum 28 and roller 8. 90

A tank or reservoir 54 for holding tarvia, an asphalt solution or other road surfacing liquid or semi-liquid, is disposed above the roller 8 and the solution is discharged through a pipe 55 extending from the rear lower portion of the tank 54 and having a transversely elongated spray nozzle or head 56 to deliver the solution to the surface of the rolled dirt, the pipe 55 having a valve 57 for controlling the flow of solution from the tank. The tank 54 is supported by transverse beams 58, and the bottom of the tank is spaced above and curved downwardly in rear of the upper portion of the roller 8 to provide a space 59 between the bottom of the 105 tank and the top of the roller.

In order to utilize the products of combustion and air heated by the flames, a jacket 60 is disposed around and spaced from the tank 54 and roller 8, to provide the vertical space 61 between the walls of the tank 54 and the jacket 60. The lower edges of the jacket 60 extend down close to the surface of the road, and the upper portion of the jacket is open for the discharge of the products of combustion and heated air. The jacket 60 has a forwardly extending entrance for receiving the portion 62 under the fuel tank 48 provided with an inlet or receiving opening 63 through which the products of combustion and heated air pass to strike the roller 8 and then pass through the spaces 59 and 61 below the tank 54 and upwardly along the walls of the tank. The roller 8 is thus heated in order that it will 120 125 130

not chill the dirt which is being packed by the roller, so that the rolling of the dirt is more effective. The tank 54 is also heated to keep the surfacing solution warm, which 5 may be necessary to make the solution flow readily through the spray nozzle or head 56.

In operation, the machine is propelled over the surface of the road to be treated, the road having been graded previously so as 10 to prepare it for treatment by the machine.

As the machine moves forwardly, the drum 28 being rotated will loosen and break up the dirt at the surface of the road to the desired depth, the blades 29 working forwardly at the bottom of the drum, to act on the dirt with a forward motion. The loosened dirt is carried upwardly by the blades 29 at the front of the drum 28 and rearwardly at the top of the drum. As the 15 blades 29 move downwardly at the rear of the drum, the dirt is thrown on the deflector 39 and passes downwardly and rearwardly over said deflector. The flames which are projected rearwardly from the burner 42 intercept the loose dirt as it falls from the deflector 39, such dirt passing through the 20 flames. As a result, vegetable matter, insects, and other combustible foreign matter will be burned and destroyed, so as to eliminate from the dirt any such foreign matter which might decay or deteriorate and thereby disintegrate the superficial layer of dirt produced by the machine. The dirt is also 25 thereby heated thoroughly, each particle of dirt passing through the flames, and the loose dirt, while heated, is piled on the roadbed in rear of the drum 28 and in advance of the roller 8. Oil is sprayed on the loose dirt in rear of the drum 28 and burner 42,

40 while the dirt is heated, thereby supporting combustion on the loose dirt to keep the dirt heated, and to also saturate the dirt with oil that is not consumed, in order that when the dirt is packed down there will be produced a hard layer 70 on the road bed 71.

The roller 8 passes over the loose dirt while same is heated and saturated with oil, so that the roller compresses or packs the dirt into a solid or homogeneous mass. The particles of dirt are baked and compressed together, so that the layer 70 will withstand the traffic conditions imposed thereon. The roller 8 in passing over and compressing the loose dirt, will also extinguish the flames 55 rising from the loose dirt. The tarvia or other surfacing solution is sprayed on the layer 70 in rear of the roller 8, thereby providing the surface 72 on the layer 70 and also serving to bond the particles of the layer 70 together, inasmuch as the solution being applied on the layer while hot and liquid will impregnate the layer 70 to some depth, thereby hardening the surface of the layer 70 and making same more homogeneous. The roller 8 being heated will also re-

sult in the layer 70 being heated when it receives the tarvia or other solution.

Having thus described the invention, what is claimed as new is:—

1. A road making machine comprising a rotary member having means thereon for engaging dirt in a roadbed and raising the dirt thereover and returning same to the roadbed as said rotary member is rotated, and means for treating the dirt raised by 75 said rotary member.

2. A road making machine comprising a rotary member having means thereon for engaging dirt in a roadbed and raising the dirt thereover and returning same to the 80 roadbed as said rotary member is rotated, and means arranged for directing flames through the dirt as the same is returned to the roadbed.

3. A road making machine comprising 85 means for loosening the dirt from a road bed and raising the loosened dirt, a deflector over which the dirt is delivered from said means to return to the road bed, and a burner arranged to direct flames from under 90 the deflector through the dirt.

4. A road making machine comprising a rotary member having means thereon for engaging dirt in a roadbed and raising the dirt thereover and returning same to the 95 roadbed as said rotary member is rotated, means arranged for directing flames through the dirt as the same is returned to the roadbed, and means for packing down the dirt while still heated by the flames passed there- 100 through.

5. A road making machine comprising a rotary member having means thereon for loosening the dirt from a road bed, raising the dirt thereover and returning the same 105 to the road bed as said rotary member is rotated, and a burner in rear of the rotary member for directing flames rearwardly through the dirt discharged from the rotary member.

6. A road making machine comprising a rotary drum having means for loosening the dirt from a road bed and raising the dirt to discharge same in rear of the drum, a deflector over which the dirt is discharged from 115 the drum, and a burner for directing flames rearwardly under the deflector to pass through the dirt as it returns to the road bed.

7. A road making machine comprising a drum having means for loosening the dirt from a road bed and raising the dirt with the drum to discharge the dirt in rear of the drum, a deflector in rear of the drum over which the dirt is discharged from the drum, a burner supported with the deflector for directing flames through the dirt, and means for mounting the drum and deflector for upward yielding movement. 120

8. A road making machine comprising a drum having means for loosening the dirt 125

from a road bed and raising the dirt to discharge the dirt in rear of the drum, an axle for the drum, means mounting said axle for upward yielding movement, a deflector in rear of the drum over which the dirt is discharged, means supporting the deflector engaging the axle for the upward swinging movement of the deflector, and a burner supported with the deflector to direct flames through the dirt.

9. A road making machine comprising means for loosening the dirt from a road bed, means for directing flames through the loosened dirt, means for spraying oil on the loosened dirt in rear of the flames, and means for packing down the loosened dirt after being sprayed with oil.

10. A road making machine comprising means for loosening the dirt from a road bed, means for packing down the loosened dirt, and means for subjecting the loosened dirt to flames and for directing the products of combustion toward the packing means to heat said means.

11. A road making machine comprising means for loosening the dirt from a road bed, a roller for packing the loosened dirt down in rear of said means, and means for directing flames rearwardly through the loosened dirt toward said roller so that the roller is heated by the products of combustion.

12. A road making machine comprising

means for loosening the dirt from a road bed, means for packing the dirt down in rear of said means, means for spraying oil on the loosened dirt between said means, and means for directing flames through the loosened dirt toward the packing means to heat the packing means by the products of combustion.

13. A road making machine comprising means for loosening the dirt from a road bed, a roller in rear of said means for packing the dirt down, a tank for a surfacing solution above the roller, means for delivering the solution from the tank to the packed dirt in rear of the roller, means for subjecting the loosened dirt to flames between the first named means and roller, and a jacket surrounding the tank and roller and having an inlet so arranged as to receive the products of combustion from the flames to pass said roller and tank for heating them.

14. A road making machine comprising means for loosening the dirt from a road bed, means for packing the loosened dirt in rear of said means, a tank, means for delivering a solution from the tank to the dirt, means for subjecting the loosened dirt to flames, and means for conducting the products of combustion from the flames adjacent to the tank for heating the tank.
